DESIGN FOR A TRAILER TANK

Ralph A. Bradley and Victor C. Norquist,
Kansas City, Mo.

Application October 12, 1934, Serial No. 53,606

Term of patent 14 years

To all whom it may concern:

Be it known that we, Ralph A. Bradley and Victor C. Norquist, citizens of the United States of America, residing at Kansas City, in the county of Jackson and State of Missouri, have invented a new, original, and ornamental Design for Trailer Tanks, of which the following is a specification, reference being had to the accompanying drawing, forming part thereof, in which

Fig. 1 is a perspective view of a trailer tank showing our new design.

Fig. 2 is a plan view of the trailer tank shown in Fig. 1.

We claim:

The ornamental design for a trailer tank, as shown.

In testimony whereof we affix our signatures.

RALPH A. BRADLEY.
VICTOR C. NORQUIST.
